UNITED STATES PATENT OFFICE.

MARTIN NARBO, OF BROOKLYN, NEW YORK.

DISPENSING FAUCET.

Application filed March 7, 1927, Serial No. 173,530, and in Guatemala March 12, 1926.

This invention relates to devices for drawing off liquid from a container, and has particular reference to an improved dispensing faucet, including means for forming an opening in the container and for attaching and sealing the faucet in said opening.

One of the principal objects of the present invention is to provide a dispensing device which in addition to affording means for puncturing and forming an outlet opening in a container, includes effectual means for rigidly connecting the device within the opening and sealing the same against leakage while allowing for detachment and removal of the device when the contents of the container are completely dispensed.

More specifically the invention comprehends an improved device for drawing off and dispensing the contents of a container, which includes telescopically associated axially movable tubular sections, one of which is provided with a stationary enlargement or peripheral abutment shoulder and the other of which is formed with a normally contracted expansible complementary shoulder operable upon relative axial movement of the sections in one direction to clamp between said shoulders a container wall around an outlet opening in which the device is positioned, the said sections being adapted upon relative axial movement in the opposite direction to cause the contraction of the expansible shoulder to permit of its withdrawal through the opening in the container wall.

The invention furthermore aims to provide means located exteriorly of the container for effecting the expansion and allowing for the contraction of the expansible shoulder.

Other objects reside in the simplicity of construction, the economy with which the device may be produced, and the general efficiency derived therefrom.

With the above recited and other objects in view, reference is had to the following specification and accompanying drawings in which there is exhibited one example or embodiment of the invention which is in no way intended as a limitation upon the scope of the appended claims as it is to be clearly understood that variations and modifications which properly fall within the scope of said claims may be resorted to when found expedient.

In the drawings—

Figure 1 is a side view of the device in applied sealed relation to the container;

Fig. 2 is a fragmentary enlarged sectional view taken approximately on the line 2—2 of Fig. 1;

Fig. 3 is a transverse sectional view taken approximately on the line 3—3 of Fig. 2.

Referring to the drawings by characters of reference, the device comprises a body member or section 10 of tubular, preferably cylindrical, formation, which is closed by a head 11 at its outer end and which is open at its inner end. The body section is formed with a boss 12 extending axially from its open end, which has an intermediate portion 13 of a reduced diameter with respect to the body 10 and forms at the juncture therewith a peripheral abutment shoulder 14. The boss 12 is provided with a still further reduced diameter 15 forming at the juncture with the intermediate portion 13, an inclined or frusto-conical spreader shoulder 16. A shank member or section 17 having an external diameter approximately equal to the diameter of the intermediate portion 13 and having an internal diameter approximately equal to the reduced diameter 15, is carried by or mounted on the boss 12 for axial movement toward and away from the abutment shoulder. The shank member or section 17 which is of tubular and preferably cylindrical configuration, has its outermost or forward end provided with circumferentially spaced inwardly extending slits 18 defining fingers 19, which render the forward or outermost end radially expansible and normally contractable. The shank section 17 is formed with a transverse web 20 having a central threaded opening 21 and apertures 22. A stem 23 is swiveled in the head 11 and is provided with an exteriorly disposed manipulating head 24. The opposite end of the stem 23 is threaded at 25 to engage in the threaded central opening of the web 20 so that upon turning movement of the stem 23, the shank section 17 is axially moved in opposite directions.

In practice the shank section has its rearmost end 26 shaped to provide a puncturing terminal which is adapted to be driven through the wall W of a container C for forming an outlet opening O therein. When the stem 23 is turned in one direction, the foremost or outermost end of the shank sec-

tion having the slits 18 and fingers 19, is moved in a direction to axially separate the shank section 17 with respect to the body section 10, allowing the slitted end to contract and so as to be of a diameter equal to or less than the diameter of the intermediate portion 13 whereby the device may be driven through the opening O in the wall W, until the shoulder 14 contacts with the outer surface 10 of the wall around the opening. When the stem 23 is rotated in the opposite direction, the shank section 17 is advanced toward or further on to the boss 12 of the body section 10, whereby the slitted end and the fingers defined thereby riding over the inclined or frusto-conical shoulder 16, expand the end so that the terminals of the fingers 19 constitute shoulders which engage behind and impinge the wall around the opening O against the abutment shoulder 14.

In addition to securely attaching the device to the container wall, it is obvious that a sealing of the shoulder thereagainst is effected while communication to the body is established through the open end of the shank section and the apertures 22 of the web. The body section 10 may have a valved outlet 27 to permit of the dispensing or drawing off of the contents. When the contents have been completely dispensed, it is obvious that by turning the stem 23 through the medium of the manipulating head 24, the shank section 17 will be moved in a rearward direction until the fingers or slitted end ride off of the intermediate portion 13 contracting to the smaller diameter of the boss so that withdrawal of the device through the opening O may be effected for removing the device from the container or receptacle.

What is claimed is:

1. A dispensing device for containers, comprising a tubular body section and a tubular shank section, said body provided with a peripheral abutment shoulder, an intermediate portion of less diameter than said shoulder, and a third portion of still less diameter over which said shank section telescopes, said shank having a radially expandable and normally contracted end, means on said intermediate portion coacting with the contractable and expandable end of the shank upon movement thereof toward the peripheral abutment shoulder for radially expanding said end to approximately the diameter of the abutment shoulder, and means for moving said sections longitudinally of each other, whereby to grip the container wall around an outlet opening in the container.

2. In a dispensing device of the character described, a tubular body section having a closed outer end, an intermediate portion of reduced external diameter defining an abutment shoulder and an inner end of further

reduced external diameter having a frusto-conical shoulder at the juncture with the intermediate portion, a tubular shank section having a rear pointed puncturing terminal and a forward end telescopically fitting over the inner end of the body section, the said forward end of the shank section being of the same external diameter as the intermediate portion of the body section and of the same internal diameter as the inner end of said body section, the said forward end being slotted inwardly from the forward edge to provide radially expandable fingers engageable with the frusto-conical shoulder upon axial movement of the shank section toward the abutment shoulder for expanding the fingers to engage with the inner side of the wall of a container around the punctured outlet opening for impinging and sealing the abutment shoulder against the outer surface of said wall.

3. A dispensing device adapted to fit in an opening in a container, comprising a pair of tubular members, one of which telescopes over the other, one of said members having a peripheral shoulder adapted to abut against the outer surface of the container, the other member having an end provided with contractable and expandable parts adapted to abut against the inner surface of the container, and means for drawing the two members toward each other, whereby the wall of the container may be clamped between said shoulders on said parts.

4. A dispensing device adapted to fit in an opening in a container comprising a pair of tubular members, one of which telescopes over the other, one of said members having a peripheral shoulder adapted to abut against the outer surface of the container, the other member having one end provided with contractable and expandable parts adapted to abut against the inner surface of the container, the other end of the last-named member formed to provide a puncturing terminal whereby to cut said opening of the container, and means for drawing the two members toward each other whereby the wall of the container may be clamped between said shoulders on said parts.

5. A dispensing device for containers comprising a tubular body section and a tubular shank section, said body section being provided with a peripheral abutment shoulder, an intermediate portion of less diameter than said shoulder, and a third part of still less diameter over which said shank section telescopes, said shank having a radially expandable and normally contracted end, means on said intermediate portion coacting with the contractable and expandable end of the shank upon movement thereof toward the peripheral abutment shoulder for radially expanding said end to approximately the diameter of the abutment shoulder, and means for moving said sections longitudinally of each other, whereby to grip the container wall around an outlet opening in the container.

- diameter of the abutment shoulder whereby to grip the container wall around an outlet opening therein, said body section having a closed outer end, and a discharge outlet between the container wall and the closed end. 5
6. A dispensing device for containers, comprising a tubular body member and a tubular shank member, said body member being provided with a peripheral abutment shoulder, an intermediate portion of less diameter than said shoulder and a third portion of still less diameter over which said shank member telescopes, said shank having a radially expansible and normally contracted end, means on said intermediate portion coacting with the expansible and contractable end of the shank upon movement thereof toward the peripheral abutment shoulder for radially expanding said end to approximately the diameter of the abutment shoulder whereby to grip the container wall around an outlet opening therein, said body member having a closed outer end, and means for effecting relative axial movements of said body and shank member, said means including a head or knob movably mounted in said closed outer end operatively connected with the shank member. 10
7. A dispensing device comprising a tubular body member having a closed outer end and an open reduced inner end providing a peripheral abutment shoulder, a tubular shank member having a pointed rearmost end for puncturing the wall of a container, said shank member being telescopically mounted on said reduced inner end of the body member and slotted longitudinally from its foremost edge to provide a radially contractable and expansible end, and means on the reduced end of the body member coacting with the slotted end of the shank section for expanding the same upon axial movement of the shank member toward said abutment shoulder, and means for moving said members telescopically of each other, whereby said slotted end cooperates with the abutment shoulder of the body member to clamp the wall of a container around an opening formed by the shank, to rigidly support and seal the dispensing device in the container opening. 15
8. A dispensing faucet for containers, comprising a pair of telescopically associated inner and outer tubular members, the inner member having a puncturing terminal adapted to be driven through the wall of a container to form an outlet opening, the outer member having a closed outer end provided with a valve and having a peripheral abutment shoulder of greater diameter than the normal diameter of the inner member, the inner member having one end expansible upon axial movement of the members toward each other, and means for moving said members longitudinally of each other, whereby to cause said end to coact with said abutment shoulder to clamp the wall of the container around the punctured outlet opening. 20
9. A dispensing faucet for containers comprising a pair of telescopically associated inner and outer tubular members, the inner member having a puncturing terminal adapted to be driven through the wall of a container to form an outlet opening, the outer member having a closed outer end and provided with a valve and having a peripheral abutment shoulder of greater diameter than the normal diameter of the inner member, the inner member having its outermost end expansible upon axial movement of the members toward each other to cause said end to coact with the said abutment shoulder to clamp the container wall around the punctured outlet opening, said end being radially contractable upon axial movement of the members in an opposite direction to permit withdrawal of the faucet from the opening, and means for moving said members longitudinally of each other. 25
10. A dispensing faucet for containers, comprising a pair of telescopically associated inner and outer tubular members, the inner member having a puncturing terminal adapted to be driven through the wall of a container to form an outlet opening, the outer member having a closed outer end provided with a valve exteriorly of the container and having a peripheral abutment shoulder of greater diameter than the normal diameter of the inner member, said inner member having its outermost end expansible upon relative axial movement of the members toward each other, whereby to cause said outermost end to coact with the peripheral abutment shoulder to clamp the container wall around the punctured opening, said outermost end upon axial movement of the members in the opposite direction being radially contractable, and interconnected means for moving said sections longitudinally of each other, whereby to permit the withdrawal of the faucet from the wall opening of the container. 30
